FRANK E. BESSEE, OF LOS ANGELES, CALIFORNIA, ASSIGNOR, BY MESNE ASSIGNMENTS, TO McDONALD SECURITIES COMPANY, LTD.

ADVERTISING DEVICE.

Application filed August 3, 1925. Serial No. 47,826.

This invention relates to advertising devices of the type in which a series of advertisements are presented to view in succession, the mechanism being actuated periodically so that there is a time of rest in which the advertising matter is displayed, after which, by a quick movement the next advertisement is brought quickly into view. While features of this invention are applicable in any situation where a display device is periodically actuated, in the present specification I have described the invention as applied to a type of rotary advertising device which carries advertising cards and presents the same to view in succession.

The general object of the present invention is to provide simple electro-magnetic means for periodically effecting the actuation of the display device, and to provide an apparatus of this kind, including an automatic switch which will be reliable in operation; also to provide simple means for regulating the period of rest during which the advertising matter is displayed.

Further objects of the invention will appear hereinafter.

The invention consists of the novel parts and combination of parts to be described hereinafter, all of which contribute to produce an efficient advertising device.

A preferred embodiment of the invention is described in the following specification, while the broad scope of the invention is pointed out in the appended claims.

In the drawing:

Figure 1 is an end elevation of an advertising device illustrating the case thereof in sectional end elevation and illustrating the same as provided with a driving and lighting mechanism embodying this invention.

Figure 2 is a front elevation of a driving mechanism embodying this invention.

Figure 3 is a sectional side elevation taken on the line 3-3 of Figure 2.

Figure 4 is a top plan view taken substantially on the line 4-4 of Figure 2.

Figure 5 is an electrical wiring diagram.

In practicing my invention, I provide display means or display mechanism of any suitable construction for carrying an advertisement. This display-means is actuated by an electro-magnetic device associated with my automatic switch. I prefer to provide a circuit with branches including two contacts corresponding to the branch circuits. The

movable switch member co-operates with the contacts to close the branch circuits alternately, and in the operation of the device an actuator moved by the electro-magnetic device operates to throw the switch from one contact to the other.

In the drawing, 1 represents the case of an advertising device. In this instance the display device consists of a rotary shaft 2 carrying a plurality of cards 4 pivotally mounted on rods 3 which connect to discs 5 rigidly carried by the shaft 2 adjacent the end walls of the case.

In order to actuate the display device, I prefer to employ a ratchet-and-pawl construction, and in the present instance I form one of the discs 5 with ratchet teeth on its edge, and rigid on the end of the shaft 2 I provide a pawl-arm 7 carrying a pawl 6. The arm 7 may be actuated by a link 8 the lower end of which is attached at 9 to the short arm of a lever 10. A detent-pawl 5^a is provided for the ratchet-wheel.

Suitable means is provided for returning the pawl arm after it has been actuated by depression of the long arm of the lever 10; for this purpose I provide a counter-weight 9^a attached to the short arm of the lever.

I provide electro-magnetic means 11 for actuating the lever 10. The switch controls the flow of electricity through two signals in the form of lamps 12 and 13, the former of which is a white light which is turned on during the display period; the red light is turned on or flashed when the movement is taking place which displays the next advertisement.

The electro-magnetic device includes a core 14 which if desired may be of the laminated type, the upper end of the core being secured by a pin 15 to the lower end of a cylinder, constituting the body of a plunger 16. This pin 15 projects considerably from the core and affords means for operating the lever 10. It is however not attached to the lever 10 but merely engages it.

In order to prevent the plunger from rotating on its longitudinal axis, I provide a guide-roller 17 which moves in a vertical channel-shaped guide 18 attached to the bed-plate 19 of the device. This roller may be carried on a reduced threaded extension from the pin 15, see Figure 3.

I provide check-means to co-operate with the plunger 16 and retard its movement in

one direction. For this purpose, I provide a fixed piston or barrel 22, the upper end of which is secured to a bracket 23 held on the back-plate 19 by screws 24. In the operation 5 of the device the plunger 16 and barrel 22 constitute a fluid-controlled check device. In the present instance I contemplate employing a liquid such as oil, and in order to enable the oil to be introduced into the 10 interior of the barrel 22, I provide a small filling opening 25 in the bracket 23, closed by a removable plug 26.

Between the interior of the barrel 22 and the plunger 16, I provide valve-means for 15 controlling the flow of the oil. This valve-means may be of any suitable construction but in the present instance includes ball valves 27 held in their valve-chambers by retaining fingers 28; the valve chambers communicate through ports 29 with the interior 20 of the barrel 22. Air vents 22^a are provided in the barrel.

In the operation of the device when the core 14 is pulled down the oil will pass 25 downwardly with relative freedom through the ports 29, but on the up-stroke of the plunger the ball valves 27 check the upward flow of the oil. I provide means for permitting a reduced flow of oil to pass between 30 the cylinders at this time, and for this purpose I provide a bleeder valve in the form of a needle-valve 30 co-operating with a bleeder port 31 formed at the bottom of a counterbore 32 in the head of the piston. 35 The valve 30 is in the form of a threaded stem mounted on the bracket 23, the head of which can be rotated to adjust the needle valve in the bleeder port.

After the core 14 has been pulled down 40 by the solenoid coil it is returned by suitable means such as two springs 33 attached at their upper ends to anchors 34 and 35 on the bracket 23. The lower end of one of these springs is attached to a groove 37 in the pin 15 and the other is attached at the point 36 to the threaded extension 20.

The solenoid coil 38 is mounted on an insulating plate 39 supported on the bed-plate 19.

In order to increase the pulling effect of 50 the coil 38, I provide a field 40 which may be of horse-shoe type and constructed of plates, that is to say, of the laminated type. This field may be supported from the bed-plate on suitable posts 40^a.

I provide an actuator in the form of an 55 arm 42 secured to an insulating block 41 by a screw 43, which also attaches the block to the side of the plunger 16, see Figure 2. This actuator is constructed so as to co-operate with a cam formed on the movable switch member in such a way that when the actuator arm is in one position it throws the switch against one contact and when it is in the opposite position it will throw the 60 switch to the other contact. In order to

accomplish this, the arm 42 is constructed of a resilient bar bent into the form of a U shaped bow, see Figure 4, and the end of this arm is attached by a screw 44 to a roller 47 which if desired may be mounted on a ball bearing 46.

The switch member 49 is in the form of a lever pivotally mounted to rotate on a fixed axis or pin 48. This lever carries the cam referred to above, at its outer end; the cam has two oppositely inclined faces 50 and 51 with which the roller 47 co-operates. The end of the lever carries a contact 54 of "carbon-pencil" type which may engage two similar fixed contacts 56 and 59 supported in brackets 57, the upper contact 56 being connected with a circuit wire 58.

Referring now to the electrical diagram shown in Figure 5, 61 and 62 illustrate the leads of the circuit which connect to a suitable source of electric current (not shown); a fuse 63 is connected in the lead 61 and this lead 61 is connected to the white lamp 12. A lead or branch 64 connects the lamp 12 with the contact 56. The lead or branch 61 is connected to a wire 65 in which a fuse 66 is connected; the lead 65 connects to one side of the coil 38 and to the red lamp 13. A lead 67 connects the opposite side of the coil 38 and lamp 12 to the contact 59.

In the operation of the apparatus when the switch lever is in its upper position, see Figures 2 and 5, the current will flow through the white lamp 12 and the display 100 of the advertising page or card will be made. During this time, however, the springs 33 are exerting their force to pull the plunger up again and will eventually move the arm 42 across the axis of the pin 48 and bring 105 the roller 47 into contact with the upper inclined face 50 of the cam. As soon as this occurs the resiliency of the arm 42 will co-operate with the cam face 50 to throw the lever 49 to its lowest position and into engagement with the contact 59. In this connection, it should be understood that the use 110 of a spring in connection with the arm 42 enables the roller to pass the apex or peak of the cam.

As soon as the switch lever has been moved down against the contact 59 the branch circuit through the coil 38 will be closed through the red lamp 13. This will effect the downward movement of the 115 plunger 16 and as soon as the arm 42 approaches the position in which it is shown in Figure 2, then the roller 47 will co-operate with the cam to throw the lever 49 back to its elevated position.

The length of time each advertising card is displayed can be controlled by regulating the needle valve 30. The air-vents 22^a enable the air to flow freely in and out of the barrel 22 so that the air within the barrel 120

will not interfere with the proper co-operation of the plunger 16 with the barrel.

As the plunger moves down the pin 15 operates the lever 10 and this operates the pawl-arm 7 and pawl 6 to rotate the ratchet-wheel 5.

If desired the counter-weight 9^a may be made sufficiently heavy to return the plunger as well as to return the pawl-arm 7.

10 It is understood that the embodiment of the invention described herein is one of the many embodiments this invention may take, and I do not wish to be limited in the practice of the invention, nor in the claims, to 15 the particular embodiment set forth.

What I claim is:

1. In a device of the kind described, the combination of display-means for carrying advertisements, an electro-magnetic device 20 for actuating the display-means, a circuit passing through the electro-magnetic device with branches for the same, including two contacts corresponding to the branch circuits, a signal in one of said branch circuits, 25 a switch member to co-operate with either contact to close the branch circuits alternately, an actuator moved in one direction by the electro-magnetic device, a spring for returning the actuator, said switch member 30 having a cam, and means carried by the actuator co-operating with the cam to throw the switch member from one contact to the other.

2. In a device of the kind described, the combination of display-means for carrying advertisements, an electro-magnetic device for actuating the display-means, a circuit passing through the electro-magnetic device with branches for the same, including two 35 contacts corresponding to the branch circuits, a signal in one of said branch circuits, a switch member to co-operate with either contact to close the branch circuits alternately, an actuator moved in one direction by the electro-magnetic device, a spring for 40 returning the actuator, said switch member having a cam, means co-operating with the cam to throw the switch member from one contact to the other, and a check-device for 45 retarding the movement of the electro-magnetic device in one direction.

3. In a device of the kind described, the combination of display-means for carrying advertisements, a solenoid coil, a plunger 50 actuated thereby, a circuit with branches, one of which passes through the coil, a signal device in one of the branches, said circuit including two contacts corresponding to the branch 55 circuits, a switch lever to co-operate with the contacts to close the branch circuits alternately, and having a cam head, an actuator for the lever carried by the plunger and having means for resiliently engaging the cam and operating in one position to 60 hold the lever in engagement with one con-

tact and in the other position to hold the lever in engagement with the other contact, and means for returning the plunger after actuation by the coil.

4. In a device of the kind described, the combination of display-means for carrying advertisements, a solenoid coil, a plunger actuated thereby, a circuit with branches, one of which passes through the coil, signals in the other branch of the circuit, said circuit including two contacts corresponding to the branch circuits, a switch lever to co-operate with the contacts to close the branch circuits alternately, and having a cam head, an actuator for the lever carried by the plunger including a spring and a roller pressed by the spring against the cam, said plunger operating to move the actuator arm to and fro across the axis of rotation of the switch lever, said actuator arm operating in one position to hold the switch lever against one contact and the other position to hold the switch lever against the other contact. 75

5. In a device of the kind described, the combination of display-means for carrying advertisements, a solenoid coil, a plunger actuated thereby, a circuit with signals and having branches, one of which passes through the coil, said circuit including two contacts corresponding to the branch circuits, a switch lever to co-operate with the contacts to close the branch circuits alternately, and having a cam head, an actuator for the lever carried by the plunger including a spring and a roller pressed by the spring against the cam, said plunger operating to move the actuator arm to and fro across the axis of rotation of the switch lever, said actuator arm operating in one position to hold the switch lever against one contact and the other position to hold the switch lever against the other contact, and fluid operated checking means co-operating with the plunger to permit a relatively free movement of the plunger in one direction and a retarded movement of the plunger in the other direction. 95

6. In a device of the kind described, the combination of display-means for carrying advertisements, a solenoid coil, a plunger actuated thereby, a circuit with signals and having branches, one of which passes through the coil, said circuit including two contacts corresponding to the branch circuits, a switch lever to co-operate with the contacts to close the branch circuits alternately, and having a cam head, an actuator for the lever carried by the plunger including a spring and a roller pressed by the spring against the cam, said plunger operating to move the actuator arm to and fro across the axis of rotation of the switch lever, said actuator arm operating in one position to hold the switch lever against one contact and in the other position to hold the 105 110 115 120 125 130

switch lever against the other contact, said plunger including a cylinder, a fixed barrel projecting into the cylinder with valve means connecting the interior of the barrel with the interior of the cylinder beyond the barrel, said cylinder and barrel co-operating to produce a checking effect on the movement of the plunger in one direction.

7. In a device of the kind described, the combination of display-means for carrying advertisements, a solenoid coil, a plunger actuated thereby, a circuit with signals and having branches, one of which passes through the coil, said circuit including two contacts corresponding to the branch circuits, a switch lever to co-operate with the contacts to close the branch circuits alternately, and having a cam head, an actuator for the lever carried by the plunger including a spring and a roller pressed by the spring against the cam, said plunger operating to move the actuator arm to and fro across the axis of rotation of the switch lever, said actuator arm operating in one position to hold the switch lever against one contact and in the other position to hold the switch lever against the other contact, said plunger including a cylinder, a fixed barrel projecting into the cylinder with valve means connecting the interior of the barrel with the interior of the cylinder beyond the barrel, said cylinder and barrel co-operating to produce a checking effect on the movement of the plunger in one direction, said barrel having a bleeder port connecting the interior of the cylinder with the interior of the barrel and co-operating with the valve means in the retarded movement of the plunger.

8. In a device of the kind described, the combination of display-means for carrying advertisements, a solenoid coil, a plunger actuated thereby, a circuit with branches including signals, one of which branches passes through the coil, said circuit including two contacts corresponding to the branch circuits, a switch lever to co-operate with the contacts to close the branch circuits alternately, and having a cam head, an actuator for the lever carried by the plunger including a spring and a roller pressed by the spring against the cam, said plunger operating to move the actuator arm to and fro across the axis of rotation of the switch lever, said actuator arm operating in one posi-

tion to hold the switch lever against one contact and the other position to hold the switch lever against the other contact, and means for returning the plunger after the same has been actuated by the coil.

9. In a device of the kind described, the combination of display-means for carrying advertisements, a solenoid coil, a plunger actuated thereby, spring means for returning the plunger after the same has been actuated by the solenoid, fluid check means co-operating with the plunger to retard the movement in one direction only, a ratchet-and-pawl for actuating the display-means, means for actuating the pawl by the plunger when actuated by the energized coil and means for returning the pawl after the same has been actuated by the plunger.

10. In a device of the kind described, the combination of display-means for carrying advertisements, a ratchet with a pawl-arm and pawl for actuating the display-means, a lever connected with the pawl-arm to actuate the ratchet, a solenoid coil, a plunger including a cylinder actuated by the coil and having means for actuating said lever when the plunger is moved by the energizing of the coil, a fixed piston cooperating with the cylinder to form a check-pot, with a valve controlling flow to and from the cylinder, spring-means connected with the plunger for returning the same after actuation by the coil, and means for returning the pawl arm after it is actuated by the solenoid.

11. In a device of the kind described, the combination of display-means for carrying advertisements, a lever with a pawl and pawl-arm for actuating the display-means, a link connected with the arm, a lever connected with the link, a solenoid coil, a plunger actuated thereby having means for actuating the lever when the plunger is moved by the energizing of the coil, spring-means connected with the plunger for returning the same after actuation by the coil, a cylinder connected with plunger, a fixed piston cooperating with the cylinder to form a check-pot with a valve controlling flow to and from the cylinder, and a counter-weight on the lever for returning the pawl-arm after it is actuated by the plunger.

Signed at Los Angeles, California, this 27th day of July 1925.

FRANK E. BESSEE.
